UNITED STATES PATENT OFFICE.

GUY LEE HAMMOND, OF WOONSOCKET, RHODE ISLAND, ASSIGNEE TO ELECTRIC COM-
POSITOR COMPANY, OF WOONSOCKET, RHODE ISLAND, A CORPORATION OF NEW
JERSEY.

LINOTYPE-MATRIX.

Specification of Letters Patent. Patented Aug. 25, 1914.

1,108,361.

Application filed August 25, 1911. Serial No. 645,914.

To all whom it may concern:

Be it known that I, GUY L. HAMMOND, a citizen of the United States, residing at Woonsocket, in the county of Providence and State of Rhode Island, have invented a certain new and useful Improvement in Linotype-Matrices, of which the following is a full, clear, and exact description.

This invention has reference to the construction of matrices such as are used in line casting machines. Such matrices are mechanically assembled in line in the desired order; are properly aligned with each other, and with a slotted mold; and are employed 15 to close one side of said mold slot so that when this slot is filled with molten type metal, a long type slug will be formed therein, which type slug will have on its printing edge a cameo replica of the characters 20 in said matrix line.

It is absolutely necessary that the matrices in a matrix line shall be accurately aligned with respect to each other, in order that the characters on the slug shall be properly 25 aligned, that is to say, shall appear to be resting upon a single straight base line.

One object of this invention is to provide the matrices, which are adapted for conjoint use, with two protected alining surfaces, so 30 placed that they will be subjected to the minimum of wear as the matrices are stored and moved from place to place, whereby these alining surfaces will be able to accurately perform their functions during the 35 useful life of the matrices. It is also desirable that the matrices of different fonts and those having characters which differ in height shall be capable of conjoint use to make a matrix line of such sort that when a 40 type slug is cast from such line, all of the characters, whether they be large or small, shall appear to be resting on the same base line. The different sized characters on the various matrices which are used in the commercial linotype machines are not so arranged on the matrices as to bring about this result. Nevertheless there are numerous 45 circumstances, as for example, in directory and catalogue work, where it is desirable to use type characters of different heights in the same line, and to have all of such characters when printed appear to be resting on the same base line.

Another object sought and obtained by this 50 invention is the introduction of matrices

adapted to conjoint use and having characters of different sizes, all arranged in such relation to the alining surfaces that when they are assembled to form a matrix line and a type slug is cast from such line, all the 50 printing characters on said slug, regardless of their height will be exactly alined at their bases.

The invention is illustrated in the accompanying drawings in which—

Figure 1 is a side elevation of three matrices whereon are characters of different height, said matrices being arranged relatively so as to show the relation between their alining surfaces and the base lines of 70 their several characters; Fig. 2 is an edge view of the same matrices similarly arranged with respect to each other.

Referring to the parts by letters A, A', A² 75 represent the matrices. The characters a on these several matrices are or may be of different heights or sizes, as for example, the character on matrix A may be five points high; that on matrix A' may be nine points high, and that on matrix A² may be twelve 80 points high. Each of these characters a is depressed into the bottom of a cup a' formed in one vertical edge of the several matrices. One horizontal matrix alining surface a² is depressed below the top edge of each matrix, 85 that is to say, it lies between the upwardly projecting spurs a³ at each side of it. Another alining surface a⁴, which is parallel with surface a², is depressed into the bottom end of each matrix, that is to say, it lies 90 between the downwardly projecting feet a⁵. In the ordinary use of these matrices, these alining surfaces a³, a⁵, are not liable to be injured or suffer wear as the matrices are 95 stored in the magazines or are caused to travel from place to place in the line casting machine. In the magazines, the bottom of one matrix rests upon the top of the matrix below it; but these alining surfaces do not engage, because it is the feet a⁵ of the upper 100 matrices which rest upon the spurs a³ of the matrices below them. Moreover, as the matrices travel through the machine, they usually rest upon the feet a⁵. These two parallel alining surfaces a², a⁴ are so placed 105 on all of the matrices adapted for conjoint use that they are a uniform distance apart. Additionally, the cups a², a' and the characters a on the different matrices (whatever 110 be the size of said characters) are so placed

in the vertical edges of said matrices, that the distances between the base line of the characters and either alining surface on any matrix are the same as those distances on any other matrix. This arrangement is clearly shown in Figs. 1 and 2, where c represents the plane of the lower alining surfaces a^1 on the different matrices; d the plane of the upper alining surfaces a^2 on said matrices; and e the plane of the base line of all the characters on the different matrices which, as stated, are or may be of different sizes.

It is quite evident that if a matrix line be made up of a variety of matrices having the relative characteristics referred to, these matrices may have characters of various sizes, but nevertheless a slug cast from such a matrix line will have all of the characters on its printing edge,—whatever be the height of such characters, exactly alined at their bases.

Having thus described my invention, I claim:

25. 1. A type matrix having two parallel horizontal alining surfaces, one facing upward and one facing downward, and other horizontal surfaces which are adjacent to said alining surfaces,—the said alining surfaces being depressed with respect to the said adjacent horizontal surfaces of said matrix.
25. 2. A type matrix having its character depression in one vertical edge and having at its upper and lower ends respectively, two parallel horizontal alining surfaces which are depressed with respect to the adjacent top and bottom surfaces of said matrix.
30. 3. A type matrix having two horizontal

parallel alining surfaces and having adjacent thereto other surfaces which project outward beyond the planes of said alining surfaces, whereby the alining surfaces are protected from frictional contact with the surfaces in a linotype machine, as the matrix is moved about in said machine.

4. A set of type matrices, each of which has two alining surfaces, one faced upward and one faced downward, which two alining surfaces are the same distances apart on all matrices, each of said matrices having also a character depression in one vertical edge, the characters being larger on some matrices than on others, and being so placed on each matrix that the distance between the base line of the character and both alining surfaces are the same as the corresponding distances on every other matrix.

5. A set of type matrices, each of which has two parallel depressed alining surfaces, one faced upward and one faced downward, which two alining surfaces are the same distances apart on all matrices, each of said matrices having also a character depression in one vertical edge, the characters being larger on some matrices than on others, and being so placed on each matrix that the distance between the base line of the character and both alining surfaces are the same as the corresponding distances on every other matrix.

In testimony whereof, I hereunto affix my signature in the presence of two witnesses.

GUY LEE HAMMOND.
